UNITED STATES PATENT OFFICE.

JAMES E. GILBERT AND GLENN W. HARRIS, OF CHICAGO, ILLINOIS, ASSIGNEES TO
GILBERT SLIP-SHEETING MACHINE COMPANY, OF CHICAGO, ILLINOIS, A COR-
PORATION OF ILLINOIS.

SAFETY TRACK FOR SMUT-SHEETING MACHINES.

Application filed March 31, 1920. Serial No. 370,261.

To all whom it may concern:

Be it known that we, JAMES E. GILBERT and GLENN W. HARRIS, citizens of the United States, residing at Chicago, county 5 of Cook, and State of Illinois, have invented a certain new and useful Improvement in Safety Tracks for Smut-Sheeting Machines, of which the following is a specification.

Patent Number 966,739 to J. E. Gilbert, 10 issued August 9, 1910, illustrates and claims a machine for taking care of sheets of printed or lithographed matter between the time they receive the impression of ink and the time they are sufficiently dried to prevent 15 offsetting when placed on a pile. Broadly speaking that machine includes the use of an intermittently moving and successively folding strip of cloth between which successive sheets of printed paper are placed 20 immediately on being printed, and in which they are carried until sufficiently dry to be automatically delivered from the machine, all as will more fully appear from the inspection of said patent.

25 The successive portions of cloth between which the paper is held are divided or marked one from another by cross bars 52 which in the operation of the machine slide downward through guides or channels 44 30 and 45 as fully set forth in said patent and when released from the bottoms of said guides they travel with the cloth back to the tops of the respective guides. It will be noticed that in said prior patent the cross bars 35 52 are on opposite sides of the continuous strip of cloth, and that no provision is made holding the bars in any given angular position with reference to the cloth from the time they leave the bottoms of the chan-

nels 44 and 45 until they return to the tops of said channel irons for reinsertion therein. As the cloth when stretched between these channels or guides must necessarily be substantially smooth and level it is essential 45 that these bars 52 always enter the respective guides in the same relative horizontal position. Actual practice has demonstrated that in the case of a machine running at the high speed of commerce these bars cannot 50 be trusted to unguided and unaided automatically assume the correct positions for entry in the guides or channels 44 and 45.

The object of this invention is to provide a continuous guide or track mechanism

which will control independently each of 55 the bars 52 on opposite sides of the stretched cloth portions from the time that they leave the bottoms of the guides 44 and 45 until they are safely reentered in proper position in the tops of said guides. 60

This invention consists broadly in means for carrying out the foregoing objects and in means for accomplishing each specific portion of the result, that is to say, it consists in detail mechanism more or less independently located at different points in the machine, which materially aids in the accomplishment of the broad general result. The invention particularly consists in such mechanism which gives thoroughly positive 70 results, and in many features and details of construction hereafter fully set forth in the specification and claims.

Before taking up the description of the drawings it may be stated for the information of the reader that the machine in question is commercially a large affair occupying about seven feet in each direction and that the track mechanism which enters largely into the invention is only about three 80 inches wide by one inch in height and contains a number of parts only about three sixteenths of an inch in thickness. The result is that it is impossible to show in the drawings in a general view all the parts constituting this invention without greatly distorting the sizes of the novel parts or their being practically invisible in the drawing. Because of this fact the single general view 85 of Figure 1 is more or less fragmentary in 90 character but the description and the detail drawings will make the matter entirely clear.

Referring to the drawings:

Figure 1 is a side view of a modern machine with the track mechanism referred to showing the application of this invention thereto in so far as is practical under the conditions just named.

Figure 2 is a plan view of the top track 100 mechanism taken over the right hand half of Figure 1.

Figure 3 is a plan view showing the single track appearing in the lower quarter of Figure 2, certain parts being shown in 105 section and more in detail.

Figure 4 is a side view of the mechanism of Figure 3.

Figure 5 is a detail end view on the line 5—5 of Figure 3.

Figure 6 is a detail side view partially in section of the lower right hand quarter of 5 the mechanism of this invention in Figure 1.

Figure 7 is an end view on the line 7—7 of Figure 6.

Figure 8 is a detail view on the line 10 8—8 of Figure 6.

Figure 9 is a plan view of the lower track mechanism taken on the irregular line 9—9 Figure 6.

Figure 10 is a detail side view of that 15 portion of the mechanism of this invention which is located in the lower left hand corner of Figure 1.

Figure 11 is a detail sectional view on the line 11—11 of Figure 10.

20 Figure 12 is a detail view of a spring portion of track cover taken at approximately the center of Figure 10.

Figure 13 is a changed position view of the parts appearing in Figure 6.

25 Figure 14 is a plan view of the essential portions of Figure 13.

The general machine shown has a pair of 30 oppositely disposed side frames 20 connected by suitable cross members of no importance herein and therefore not shown in detail. Mounted in this general frame are front guides which for uniformity with the prior Gilbert patent are designated 44 and rear guides correspondingly designated 35 45 performing in general terms the function of the correspondingly designated members in said prior patent.

As in said prior patent a continuous strip 40 of cloth 22 is provided divided by successive cross bars 24 and 26, adapted respectively to travel down guides 44 and 45 into successive sections referred to in the prior patents as print sheet supports and smut sheets.

This continuous strip of cloth carrying 45 these bars 24 and 26 is propelled and ultimately stretched to the positions of Figure 10 by a power roller 28 supported by trucks carried on wheels 30 traveling in tracks 32 and driven by a lever mechanism 34, 36 in 50 turn driven by the crank or stud 38 on disk 39 and rotated by power shaft 49. As is fully set forth in said Gilbert patent this roller 28 is driven to the left as viewed in Figure 1 far enough so that at each cycle 55 of operation one bar 24 is deposited in guides 44, after which the roller returns to the right a sufficient distance to the right of guides 45 so that the next adjacent bar 26 can be and is deposited in the guides 45, 60 whereupon the roller 28 again starts to the left carrying over another section of cloth and deposits a new bar 24. As in said prior patent the cloth engages at the bottom of the machine another roller 42 which performs all the functions of the roller 80 of

said Gilbert patent as set forth therein, it being in the particular case here illustrated moved to the left of Figures 1, 6, 9, 13 and 14 by a dash pot-mechanism, (not shown) attached to straps or belts 46 which dash pot 70 mechanism is the subject matter of a pending application heretofore filed by us. The modern commercial machine described up to this point operates to move the cloth into, through and out of the guides 44 and 75 45 in the same cycle of operations set forth diagrammatically in Figures 21 to 28 inclusive of said prior Gilbert patent.

As heretofore, indicated, the principal object of this invention is to, in the continuous movement of the cloth, guide and control each cross bar 24 from the time it leaves the bottom of the guides 44, while it travels entirely around the pile of folded-in cloth 22 until it is ready to re-enter the tops of 85 said guides 44 and to simultaneously control the cross bars 26 as they successively leave the bottoms of the guides 45 and travel to the point where they are above the upper entrances of said guides 45 and are ready 90 to be moved by suitable mechanism one form of which will be described, into said guides. Broadly speaking, this result is accomplished by providing a normally continuous track or channel designated as an 95 entirety 50, leading from the lower exits of guides 44 to a point immediately adjacent to their upper entrances, this with and without switching mechanism located adjacent to the lower exits of guides 45 through 100 which bars 26 may be inserted in the tracks and carried around to the upper entrances of guides 45 and the provision there of means for moving or switching out these bars 26 from the tracks so that they enter 105 the upper entrances of said guides 45. Each track 50, (there is one on each side of the machine) is, in order to allow for the normal travel of the roller 42, made with an inclined section 50^a, shown in detail in Figure 10, immediately adjacent to the lower ends of the adjacent guides 44. This portion of track merges into a continuous and a generally straight section 50^b along the underside of the machine and below the 115 lower ends of guides 45 which curves into section 50^c around roller 52, corresponding to roller 100 of said prior Gilbert patent. This lower section 50^{a-b} of track 50 is covered by a member 54 running substantially 120 parallel to the bottom member and is so spaced therefrom as to retain the cross bar 24 in the horizontal position in which it enters the track when it was released from the pile of cross bars 24 shown in Figure 10 by 125 the releasing latch mechanism 56. This latch mechanism 56, without novelty in this application, and therefore not described in detail, merely performs the same function as the correspondingly releasing mechanism 130

of said Gilbert prior patent. The track cover 54 is adjacent to the bottom of guide 44 made flexible by the use of a spring 58 attached to the bottom of the guide 44 by 5 any suitable means, for instance as shown in Figure 12. The function of this spring 58 is two-fold: (a) it contracts the entrance to the track 50 to such an extent that the dropping bar 24 released by mechanism 10 56 cannot possibly turn over as it enters the trackway and (b) it allows the cover 54 of the track, to yield slightly as the roller 42 reaches its extreme left hand position. By the use of this spring construction the 15 roller 42 can travel a maximum distance to the left as viewed in Figure 10 thereby performing its proper function in preventing bagging of the cloth as the bar 24 is released which bagging of the cloth is well understood in the art to be very detrimental to 20 the proper delivery of the printed sheets of paper, i. e. to the proper operation of the machine. From the wheel 52 heretofore referred to, the track 50 leads over the roller 25 60 corresponding in function to rollers 58 of said prior Gilbert patent, the cover member 54 below now becoming bottom member 54^a, and then leads along the top of the machine to a point 62 slightly to the right of 30 the side walls of the guides 44, at which point the confined cross bars 24 are released and are turned over by and around the roller 28 in the act of being deposited by said roller in position to descend the 35 guides 44.

The member 54, heretofore referred to, as the cover of section 50^a of track 50 terminates at a point 64 a little to the left of the lower end of the adjacent guide 45. 40 Horizontally slidably in substantial alignment with this end 44 is the lower side 66 of a U-shaped bar whose opposite side arm is lettered 68 the two members being connected by the vertical member 70 forming the bottom of the U referred to. This lower member 66 is reciprocably mounted 45 on the under side of a stationary plate 72 which forms the upper guiding portion of section 50^b of track 50. Rising from member 72 is a stationary post 74 to which is connected a spring 76 connected at its opposite end to a post 78 carried on member 66 and extending through an elongated slot 80 in member 72. The result of this construction is that the spring 76 tends to hold 50 the U-shaped member referred to in the position shown in Figure 6 and return it to that position when it has been moved to the position of Figure 13 by the roller 42 55 engaging it and moving it as shown in that figure.

The parts just described are so located and positioned with reference to all the moving parts of the machine that when 60 mechanism forming no part of this inven-

tion moves latch mechanism 82 to release lower bar 26 from the pile of bars in guides 45 roller 42 simultaneously moves U-shaped member 66-68 to the right against the action of spring 76 until this lower bar 26 65 as clearly shown in Figure 13, descends over and around that roller through the position of Figure 13 until it reaches its normal carrying position of Figure 6, in track 50 during which latter mentioned movement 70 member 66-68 has closed the top of the track as shown in Figure 6. The result of this operation is that the bottom bar 26 has been transferred from the bottom of the pile in guides 45 into the position 80 shown in the track 50 in Figure 6 where it is ready to be carried continuously in that position around the wheels or rollers 52 and 60 up to the position where it is over the upper entrances of the guides 45 and ready 85 to be switched or moved out of the track and down into said guides.

The use of U-shaped member 66-68 is important in that lower member 66 passes under member 72 thus rendering the upper 90 inside track surface smooth for passing bars 24 when they come along while upper member 68 forms a convenient guide and track for the passage of bars 26 from the guides into the track 50.

In the practical operation of the machine the law of the machine is such that the bar 26 when deposited in the track in the position of Figure 6 does not immediately move or is not immediately moved by the pull of 100 the cloth as just described, but this is immaterial so far as the invention of this application is concerned. The portion 54^a of the track immediately over guides 45 is provided with a set of slots and notches shown 105 in plan view of Figure 3, the same being provided with closing mechanism, timed to be in place as each bar 24 passes so that for that bar the track portion is practically smooth and timed to be opened in the operation of the machine at the proper moment for the next adjacent bar 26 to be carried down into the adjacent guides 45.

The device just referred to includes a transverse parallel sided slot 90-91 of sufficient width and depth so that the adjacent end of the cross bar 26 can pass downward through it; a longitudinal slot 92 so that the gripping jaw mechanism 94, which merely exemplifies one of many types 115 which may be used, can pass up through this slot 92 and take the adjacent bar 26 into the space 96 provided for the purpose and carry the bar down into the guide 45. Furthermore, and very essential, there is 120 provided a longitudinal slot 98 in which a closure bar 100 is adapted to reciprocate from the position of Figure 3 in which it closes or bars slot 90 and thus allows cross bar 24 to pass over the track at this point 130

to and towards guide 44. This slot 98 is of such a length that when the member 100 is moved to the right to the extreme end of slot 98 slot 90 is opened vertically for the downward passage of bar 26. Member 100 is supported on and reciprocatable with a plate 102 seen through slot 98 in Figure 3, reciprocatably mounted in brackets 104 for movement on the underside of member 54^a. This plate 102 and block 100 is reciprocated automatically in the operation of the machine by lever arm 105 and connecting rod 106 carried on a shaft 108. Rigid with arm 105 and forming a bell crank 15 arm therewith is a lever arm 110 connected by a link 112 to a reciprocatable cross head 114 which actuates the gripping jaws 94 heretofore referred to. This cross head is reciprocated through a connecting rod 116 20 driven by a cam and lever mechanism 118, 120, driven by shaft 40, heretofore referred to. These parts are so timed that when the top roller 28 is in the proper position at the top of the machine where the adjacent 25 bar 26 should enter guides 45, that bar is on the track portion 54^a over member 100, whereupon that member slides to the right to open the slot 90, whereupon the jaws 94 simultaneously move up and grip the bar 30 and carry it down into the guides 45, during which time, the motion of member 100 is reversed, thereby closing slot 90 and keeping it closed until it is time for another bar 26 to be moved into the guides 45. 35 During the intervening time another bar 24 will have been passed along the track over member 100 to point 62 ready for entry in guides 44 and in such movement will have had a smooth passage because of the proper 40 closing of slot 90 by member 100.

It is to be noted that the cam and lever mechanism is such that when member 100 closes slot 90 it is held positively in that position and the slot cannot accidentally 45 open and let a passing bar 24 either catch or actually pass down into the guides 45.

The detail mechanism for opening and closing the jaws 94 is not shown in detail because any sort of mechanism for this purpose might be used and this particular mechanism is to be the subject of a companion application hereafter filed by us.

Having thus described our invention what we claim as new and desire to secure by 55 Letters Patent, is:—

1. In a machine of the class described, in combination with front and rear vertical guides, and a piece of cloth carrying front and rear cross bars adapted to travel down 60 said guides, guiding tracks for a front bar, leading from the bottoms of the front guides, below, around, and over the rear guides to the upper ends of the front guides whereby a front bar on the cloth is continuously guided and positioned in passing 65

with the cloth from the lower ends of the front guides around to their upper ends.

2. In a machine of the class described, in combination with front and rear vertical guides, a piece of cloth carrying front and rear cross bars adapted to travel down said guides and means for moving the cloth from a position in which said bars are in the bottoms of said guides to a position in which they reenter the tops of said guides; guiding tracks for a front bar, leading from the bottoms of the front guides, below, around, and over the rear guides to the upper ends of the front guides whereby a front bar on the cloth is continuously guided and positioned in passing with the cloth from the lower ends of the front guides around to their upper ends. 70 75 80

3. In a machine of the class described, in combination with front and rear vertical guides, and a piece of cloth carrying front and rear cross bars adapted to travel down said guides, guiding tracks for a front bar, leading from the bottoms of the front guides, below, around and over the rear 90 guides to the upper ends of the front guides whereby a front bar on the cloth is continuously guided and positioned in passing with the cloth from the lower ends of the front guides around to their upper ends, and means for guiding the rear bar from the bottoms of said rear guides into the said track whereby it is positioned while being carried around to the upper ends of said rear guides. 95 100

4. In a machine of the class described, in combination with front and rear vertical guides, a piece of cloth carrying front and rear cross bars adapted to travel down said guides, and means for moving the cloth from a position in which said bars are in the bottoms of said guides to a position in which they re-enter the tops of said guides, guiding tracks for a front bar leading from the bottoms of the front guides below, around, and over the rear guides to the upper ends of the front guides whereby a front bar on the cloth is continuously guided and positioned in passing with the cloth from the lower ends of the front guides around to their upper ends, and means for guiding the rear bar from the bottoms of said rear guides into the said track whereby it is positioned while being carried around to the upper ends of said rear guides. 105 110 115 120

5. In a machine of the class described, in combination with front and rear vertical guides, and a piece of cloth carrying front and rear cross bars adapted to travel down said guides, guiding tracks for a front bar leading from the bottoms of the front guides below, around, and over the rear guides to the upper ends of the front guides whereby a front bar on the cloth is continuously guided and positioned in passing with the 125 130

cloth from the lower ends of the front guides around to their upper ends, means for guiding the rear bar from the bottoms of said rear guides into the said track whereby it is positioned while being carried around to the upper ends of said rear guides, and means for taking said bar from the last mentioned position into the upper end of said rear guides.

10. 6. In a machine of the class described, in combination with front and rear vertical guides, a piece of cloth carrying front and rear cross bars adapted to travel down said guides, and means for moving the cloth 15 from a position in which said bars are in the bottoms of said guides to a position in which they re-enter the tops of said guides; guiding tracks for a front bar, leading from the bottoms of the front guides below, 20 around and over the rear guides to the upper ends of the front guides whereby a front bar on the cloth is continuously guided and positioned in passing with the cloth from the lower ends of the front guides around 25 to their upper ends, means for guiding the rear bar from the bottoms of said rear guides into the said track whereby it is positioned while being carried around to the upper ends of said rear guides, and means for 30 taking said bar from the last mentioned position into the upper end of said rear guides.

7. In a machine of the class described, having vertical front and rear guides, and a continuous foldable cloth carrying bars 35 adapted to alternately enter said front and rear guides, and means for so carrying said cloth and said bars that a bar leaving the bottoms of the front guide is carried around to the upper entrances of said guides and 40 the next adjacent bar leaving said rear guide is carried around to the upper entrances of said rear guide; a continuous track leading from points adjacent to the respective exits of said guides following approximately the path of travel of said cloth as it 45 moves from said guide exits to said guide entrances as described, said track being shaped to hold the respective cross bars in predetermined positions as they travel from 50 the exits of the guides to the guide entrances, means adjacent to the exits of the respective sets of guides for entering bars delivered therefrom into said track, and means adjacent to the entrances of each set of guides 55 for delivering each bar on the track for that particular set of guides into the proper guides when they are reached by that particular bar.

8. In mechanism of the class described, 60 a smut sheeting machine having vertical guides for the passage of bars attached to different portions of cloth carried by the machine, and a continuous track communicating with all guides at their exits and delivering to all guides at their entrances

adapted to position and retain each and every bar attached to the cloth in proper position from the time it leaves the guides to which it belongs until it is ready to re-enter said guides.

9. In mechanism of the class described, a smut sheeting machine having vertical guides for the passage of bars attached to different portions of cloth carried by the machine, and a continuous track communicating with all guides at their exits and delivering to all guides at their entrances adapted to position and retain each and every bar attached to the cloth in proper position from the time it leaves the guides to which it belongs until it is ready to re-enter said guides, switching mechanism arranged in the track adjacent to guides which have to be passed by any particular bar in going to its own guide adapted to insure the passage of such bar to its own guide and openable for the passage of the bar which belongs to the guide adjacent to which the switch is located.

10. In a machine of the class described, a vertical guide down which bars attached to cloth may pass, means at the bottom of said guide for normally retaining a pile of bars in said guide, a trackway below and leading away from said guide for the reception of a bar delivered from said guide, and a spring wall adjacent to the entrance of said trackway, for the purposes set forth.

11. In mechanism of the class described, a vertical guide for cloth carrying bars, 100 mechanism temporarily supporting bars in said guide, a roller reciprocatable under the end of the guide up to a point in close proximity to said guide, a closed trackway adapted to receive bar carried from said 105 guide, and a spring member in the wall of the trackway engaged by the roller in its movement to allow maximum movement by the roller.

12. In mechanism of the class described, a 110 guide adapted to have a bar pass through it, a normally closed track extending transversely of said guide adjacent to its end, a door in said track adjacent to said guide, and means for opening said door, to admit a 115 bar from said guide into said track.

13. In mechanism of the class described, a guide adapted to have a bar pass through it, a normally closed track extending transversely of said guide adjacent to its end, a 120 door in said track adjacent to said guide, and automatic means operable by the machine as a bar passes from said guide for opening said door, to admit a bar from said guide into said track.

14. In mechanism of the class described, a 125 guide through which a bar may pass, a normally closed track passing transversely to the bar adjacent to its end, a slidable door in said track and means for reciprocating said 130

door to admit a bar from said guide to said track.

15. In mechanism of the class described, a guide through which a bar may pass, a normally closed track passing transversely to the bar adjacent to its end, a slidable door in said track, and automatic means operable by the machine as a bar passes from said guide for reciprocating said door to admit a 10 bar from said guide to said track.

16. In mechanism of the class described, a guide through which a bar may pass, a transverse closed track adjacent to the end of the guide, a horizontally disposed U-shaped member between the guide and the adjacent wall of the track, one side forming a door for the track, spring means urging said U-shaped member to the position where it closes the track, and a reciprocatable member traveling parallel with the track adapted to strike said U-shaped member and so move it against said spring that a bar in the guide can pass into the track.

17. In mechanism of the class described, a vertical guide through which a bar may pass, a closed track member below the end of the guide, extending crosswise of it, a U-shaped member 66—68 interposed between the bottom of the guide and the track, one 25 side 66 of the U-shaped member constituting a sliding door member traveling on the inside of the upper wall of the track, to close an opening in the track adjacent to the guide, and spring mechanism urging said 30 U-shaped member to such a position that the track is normally closed, for the purposes set forth.

18. In mechanism of the class described, a vertical guide down which a bar may pass, a track passing over the upper end of said 40 guide, provided with a door opening over said guide, a door normally closing said opening, means co-operating with the guide adapted to be moved through said door opening in the track to remove a bar therefrom into the guide, and mechanism automatically opening said door, moving said 45 bar removing mechanism through the door, retracting it and closing said door for the 50 purposes set forth.

19. In mechanism of the class described, a track mechanism, an adjacent guide for the passage of a bar, previously carried by the track to a point adjacent to the guide, a

door in the track adjacent to the guide, 55 means in connection with the guide adapted to be moved through the door opening in the track to grip a bar therefrom and place it in the guide, and positively operating automatic mechanism, opening the door in the 60 track, manipulating the gripping mechanism through the door, retracting the gripping mechanism, and closing the door.

20. In mechanism of the class described, a horizontal track having a transverse perforation 90—91 for the end of a bar, a slot 92 at right angles thereto for the passage of gripping jaws, a closing bar or door 100 reciprocatable longitudinally of the track between two positions in one of which it 70 closes or bars said passage 90 and in the other of which it leaves it open, means on the under side of the track for reciprocating said bar 100 all of the parts being arranged and disposed as shown and described, for 75 the purposes set forth.

21. In mechanism of the class described, in combination with front and rear vertical guides adapted to have bars pass down them, a track over the rear guide leading to and terminating at a point adjacent to the front guide, a cloth carrying roller reciprocatable substantially parallel to said track to carry cloth, carrying a cross bar over the rear guide, across the machine to a point adjacent to the front guide, and to deposit a bar carried by the cloth in said front guide, means for driving said cloth carrying roller, a door mechanism in the track adjacent to the rear guide and over which the bar going 80 to the front guide passes, gripping mechanism adapted to pass from a point in proximity to the rear guide through said door in the track to grip a bar at that point, mechanism operated by the same mechanism which 85 actuates the roller for positively operating said door and said gripping mechanism to take the bar from the track into the adjacent guide, the whole being so timed that the separate bars are deposited in the two 90 sets of guides at proper predetermined times.

In witness whereof we have hereunto subscribed our names.

JAMES E. GILBERT.
